UNITED STATES PATENT OFFICE.

WALTON STANLEY TOPE, OF LONDON, OHIO.

HOTBED-SASH PROP.

1,360,827.

Specification of Letters Patent. Patented Nov. 30, 1920.

Application filed May 24, 1920. Serial No. 383,863.

To all whom it may concern:

Be it known that I, WALTON S. TOPE, a citizen of the United States, residing at London, in the county of Madison and State 5 of Ohio, have invented new and useful Improvements in Hotbed-Sash Props, of which the following is a specification.

The object of my present invention is the provision of a simple, easily positioned and 10 safe prop through the medium of which a sash of a hot-bed may be supported and held open to a greater or less extent as conditions require.

To the attainment of the foregoing, the 15 invention consists in the improvement as hereinafter described and definitely claimed.

In the accompanying drawings, hereby made a part hereof:

Figure 1 is a view on a small scale illustrative of the application of my novel hotbed sash prop.

Fig. 2 is a side elevation of the prop *per se* on an enlarged scale.

Fig. 3 is a longitudinal vertical section 25 through the upright of the prop, and showing the arrangement of the sash-supporting platform relatively to the upright.

Fig. 4 is a horizontal section taken in the plane indicated by the line 4-4 of Fig. 2, 30 looking downwardly.

Fig. 5 is a detail elevation illustrative of the inner side of the upright of the prop.

Similar numerals of reference designate 35 corresponding parts in all of the views of the drawings.

Among other elements my novel prop comprises a base 1, designed to be superimposed on the frame of a hot-bed. The said base 1 is preferably 4 inches in length, $\frac{1}{2}$ 40 of an inch thick, and 2 inches wide, and is provided at its upper side with a longitudinal central rib 2 that is $\frac{1}{4}$ of an inch high at the upright 3 and is gradually tapered in height and thickness to the outer 45 end of the base 1 where it is merged into the upper side of the base as shown.

The upright 3 is fixed with respect to and rises at right angles from one end of the base 1. The said upright 3 is preferably 50 $12\frac{3}{4}$ inches in height, $\frac{1}{2}$ inch wide at its inner side and $\frac{5}{8}$ of an inch in thickness, and in its inner side and longitudinal center it is provided with ten (more or less) notches 4; the lowest notch being $\frac{1}{8}$ of an inch deep and the

notches being gradually increased in depth 55 as they approach the upper end of the said upright, the upper notch being $\frac{1}{4}$ of an inch deep.

The prop also comprises an adjustable platform 5. The said platform 5 is preferably $\frac{1}{4}$ of an inch thick, $1\frac{1}{2}$ inches wide from its forward end to an intermediate point 6 in its length, and is tapered from the said intermediate point 6 to its rear end where it is preferably $\frac{1}{2}$ of an inch wide. 65 On its forward end portion the platform 5 is provided with a cross-strip 7, designed to preclude a sash slipping off the platform. In the platform 5 is an oblong aperture 8 that is preferably $\frac{1}{16}$ of an inch wide and $\frac{3}{4}$ 70 of an inch long, and is disposed in the center of the platform. At its under side the platform 5 is provided with a clutch 9 that is preferably $\frac{3}{4}$ of an inch in length and $\frac{1}{16}$ of an inch in thickness and is inclined as 75 shown.

As will be understood by comparison of Figs. 2 and 4, the platform 5 is arranged on and supported by the upright 3, and when the hot-bed sash is laid on the platform, the 80 clutch 9 enters one of the notches 4 in the upright 3 and thereby firmly holds the platform 5 and the sash thereon against downward movement. In this connection it will be observed that when the platform 5 is 85 clutched to the upright 3, the platform will have the natural slope of the sash.

Having described my invention, what I claim and desire to secure by Letters-Patent, is:

A prop for hot-bed sash, comprising a base and an upright fixed to and rising at right angles from one end of the base, the base having at its upper side a longitudinal central rib that extends from the inner side 95 of the lower portion of the upright, and the upright having in its inner side a vertical central series of notches gradually increased in depth as they approach the upper end of the upright, and a platform with rear and 100 forward arms, having an oblong aperture loosely receiving the upright, and an inclined clutch at its under side to seat in the notches of the upright and also having on the upper side of its forward arm at the end 105 thereof a cross-strip.

In testimony whereof I affix my signature.
WALTON STANLEY TOPE.
